SERGE JNN. MOUROMOFF, OF ST. PETERSBURG, RUSSIA.

GAGE-COCK FOR USE ON STEAM-BOILERS.

1,106,105.

Specification of Letters Patent.

Patented Aug. 4, 1914.

Application filed May 2, 1913. Serial No. 764,988.

To all whom it may concern:

Be it known that I, SERGE JNN. MOUROMOFF, engineer, subject of the Emperor of Russia, residing at No. 10 Alekseevskaya street, Lessnoi, St. Petersburg, in the Russian Empire, have invented new and useful Improvements in Gage-Cocks for Use on Steam-Boilers, of which the following is a specification.

10 In connection with steam boilers it is usual to provide two gage cocks, one of which is above the maximum water level, while the other is below the minimum water level.

15 Under normal conditions only steam should appear when opening the upper cock and when opening the lower, only water should flow. Since however, the steam condenses very rapidly and the superheated 20 water when entering into space of atmospheric pressure partly evaporates, it is difficult to tell by inspection whether it is water or steam which escapes. Such gage cocks furthermore only permit of observing the 25 water level in the boiler at the moment of opening the cock, although it is of great importance for the supervision of the boiler to know whether any undesirable fluctuations 30 of the water level are taking place during a certain interval of time.

According to my invention the gage cocks are so arranged that they show at a glance whether steam or water is at the height where the cocks are fitted, and it is also 25 rendered possible to see whether the water level in the boiler has been fluctuating beyond the fixed limits after the previous observations. For this purpose the gage cock 35 housings are provided with transparent receptacles in which floats are adapted to move. If the water level has not risen or fallen beyond its normal limits, there will be steam in the upper receptacle and water in the lower, whereby the floats can be seen 40 in both the receptacles. Should however, the water have risen beyond the maximum or fallen beyond the minimum level, the float in the corresponding receptacle will 45 not be seen.

50 In the accompanying drawings my invention is illustrated by way of example.

Figure 1 shows my improved gage cocks in side elevation and fitted to a steam boiler. Figs. 2 to 4 are three modifications of the 55 arresting device. Fig. 5 is a side elevation of a modified form of the device.

In the drawings A and A' are the transparent receptacles which communicate with the housings E and E' and which contain the floats D and D'. Perforated plates R 60 and R' are also arranged within the receptacles, which plates are provided with weights O, O'. A connection between the receptacles and the boiler is established by means of the pipes B and B' which are arranged at the height of the minimum and of the maximum water level respectively in the boiler. The weights O and O' are made so that the weight O is only slightly heavier than its plate R, and weight O' only 65 slightly heavier than plate R'. Thus the float D can by its weight easily depress the plate R while the float D' on account of its buoyancy is capable of lifting the plate R'. 70

The device operates in the following manner: When the water in the boiler rises beyond the maximum level H, for example as far as I, it closes the entrance for the steam into the pipe B', thus the steam contained in the receptacle A' condenses and water will 80 enter through the pipe and rise into the receptacle. The float D' is thereby caused to ascend into the casing E', it lifts the plate R' which immediately closes again and thus entraps the float in the said casing. When 85 afterward the water level in the boiler falls again, the casing E' again fills up with steam, but the float D' is prevented from going back into its initial position in the receptacle A'. The disappearance of the float 90 from the receptacle proves that the water in the boiler had risen to above the maximum gage level. When on the other hand the water in the boiler falls to below the minimum gage level N, for example as far as T, 95 the passage through the pipe B becomes free and the water from the receptacle A and casing E flows into the boiler whereby the float D falls and displaces the plate R. On the water in the boiler rising, the steam in 100 the receptacle and casing condenses and the space is filled up with water, while the float is arrested by plate R and entrapped in the casing E. It can thus be seen, that the water in the boiler had been below the minimum level. In order to replace the floats into their receptacles A and A', the taps P 105 and P' must be closed, the plugs G and G' unscrewed and the covers M and M' detached. After the floats have been replaced and the previously detached parts 110 have been refitted, the taps P and P' are

opened again and may be sealed or otherwise marked so that only authorized persons will have access to same. This having been done, the taps K and K' are opened for 5 a short time in order to make sure that the proper connection has been re-established between the receptacles A, A' and the boiler and to replace the air in receptacle A' with steam.

10 Instead of the aforesaid device any of the modifications which are shown in Figs. 2 to 4 may be used.

The device as illustrated in Fig. 2 consists of a spiral-shaped surface F which may be 15 provided in the casing E and below which chambers U are arranged. Along this spiral the float D can move downwardly with the falling water level as indicated by the arrow. When the water subsequently 20 rises, the float rises also and is caught in one of the chambers U as shown in the figure at D². A similar device is arranged in the casing E', but there the chambers U are provided above the spiral surface F instead of 25 below, so that the float can freely move in an upward direction but will be arrested when going downward.

The devices shown in Figs. 3 and 4 illustrate very simple forms of the float arresters in which funnel-shaped or simply obliquely arranged surfaces V² and V' are 30 arranged in staggered manner in the casings

E, E'. Their operation is substantially the same as that described with reference to Fig. 2. The receptacle A, A', may be made entirely transparent or they may be provided with a transparent window as indicated at 35 S in Fig. 5.

Having now particularly described and ascertained the nature of my said invention 40 and in what manner the same is to be performed, I declare that what I claim is:—

In water gage cocks for use on steam boilers and for indicating the maximum and minimum water levels in combination, two 45 transparent receptacles, connections between said receptacles and the boiler, a float in each of said receptacles, one of which floats is adapted to rise when the water in the boiler rises above the maximum level where- as the other float sinks down when the water in the boiler falls below the minimum level, and means for arresting the floats in their highest or lowest positions respectively, and preventing their return into the receptacles 50 even if the water level re-assumes its normal position.

In testimony whereof I have signed my name to this specification in the presence of two subscribing witnesses.

SERGE JNN. MOUROMOFF.
